UNITED STATES PATENT OFFICE.

OSCAR C. RIXSON, OF NEW YORK, N. Y.

HINGE.

1,125,177.

Specification of Letters Patent. Patented Jan. 19, 1915.

Application filed June 8, 1912. Serial No. 702,845.

To all whom it may concern:

Be it known that I, OSCAR C. RIXSON, a citizen of the United States, and a resident of the city, county, and State of New York, 5 (whose post-office address is 5 East Forty-second street, New York city, New York,) have invented a new and useful Improvement in Hinges, which invention is fully set forth in the following specification.

One object of my invention is to provide hinges by which the door may be raised or lowered without removing the hinges.

Another object is to provide hinges that can be used as right-hand or left-hand 15 hinges at will.

The invention consists of the features of construction and arrangement hereinafter pointed out and claimed, and will be best understood by reference to the annexed 20 drawings and description, which set forth a preferred embodiment thereof.

In the drawings.—Figure 1 is a vertical section through the two hinge-members; and Fig. 2 is a horizontal section through 25 a portion of a doorway and an adjacent door, secured thereto by a pair of my new hinges.

In the drawings, 1 represents the door to which is attached one hinge-plate 2, that 30 carries an offset knuckle 3 with its open-bottomed socket.

4 is a plug of hardened steel having a concave seat, and preferably provided with one or more "burs" 5. This plug 4 has been 35 driven forcibly into the bottom of the socket in knuckle 3, the burs preventing it from dropping out during shipment.

6 is a ball of hardened steel, positioned in the concave seat of plug 4, and held in 40 place as by a spiral spring 7.

8 is the door-facing or jamb, to which is secured the other hinge-plate 9, that carries the offset knuckle 10 having a bore open 45 from end to end and provided with internal screw-threads. The hinge-pivot consists of

the cylindrical plug 11, of hardened steel, screw-threaded around its lower portion to engage the internal threads in knuckle 10, and preferably concaved on its other end 50 to receive the ball 6. The lower end of this pivot-plug 11 is transversely split, at 12 and 13, and has an internally-threaded bore into which turns the tapering set-screw 14.

15 is a plug or closure, screw-threaded

into the lower end of the larger bore in 55 knuckle 10.

To raise (or lower) the door, the closure-plug 15 is unscrewed, and so is the set-screw 14; after which the pivot-plug 11 is screwed either up or down as desired, thus varying 60 the height of its upper end which supports the other hinge-member and the door; and when the proper adjustment has been attained, the set-screw 14 is forced home, thus spreading out the split screw-portion of the 65 pivot-plug 11 and locking it securely in place, after which the closure plug 15 is put back as before.

Referring to Fig. 2, it will be seen that the axis of the hinge-member 3 lies in substantially the median plane, indicated by dotted line 16—16, that passes through its fastening-plate 2 (instead of being in the plane of the crack between the door and the doorway, as heretofore); while the axis of 70 the other hinge-member is so offset as to coincide with the axis of the first hinge-member. By means of this construction and arrangement, the pair of hinges may be employed, as indicated in Fig. 2, as "left-hand" hinges (i. e., the hinges are at the left of the door). To employ the members as "right-hand" hinges, the plugs 15 and 11 are removed from their hinge-member (the closure-plug 15 being unscrewed as by hand, 75 then the set-screw 14 removed, after which the pivot-plug 11 can be entirely withdrawn through the bottom of the knuckle 10), and then said hinge member turned upside down, and the plugs 11 and 15 inserted into 80 proper position. This arrangement brings the parts into the position indicated by dotted lines in Fig. 2, in which the hinge-plate 2 may be secured to the right-hand side or edge of the door, and the other member 85 (now represented by the dotted line 9') may be secured to the right-hand door-facing,—thus constituting the pair of "right-hand" 90 hinges.

It will be understood that modifications 100 may be made in the construction and arrangement of the parts, that the parts may be inverted or transposed, and that some features may be used to the exclusion of others, without in any instance departing from the 105 spirit of my invention. For instance, instead of having a continuous bore through the knuckle 10, there may be one screw-

threaded socket at the top and a separate screw-threaded socket at the bottom (with the screw-threaded pivot 11 detachably and adjustably seated in either of said sockets); 5 or, the bore may extend entirely through this knuckle, yet be screw-threaded in only a portion thereof.

Having thus described my invention, I claim:

- 10 1. The combination of a hinge-member having a socket whose axis lies in substantially the median plane of its fastening-plate, a second hinge-member having a bore whose axis is in that same plane, a detachable pivot adjustably held to protrude from either end of said bore to receive said socket, and means for locking said pivot in place.
- 15 2. The combination with a hinge-member which has a socket in which is held a ball, 20 of a second hinge-member having a bore open at each end, a detachable pivot protruding adjustably from either end of said bore and adapted to enter said socket and present its end as a bearing for said ball, 25 and means for locking said pivot in place in said bore.
- 30 3. The combination of a hinge-member having a socket, a second hinge-member having a screw-threaded bore open at each end, 35 and a pivot adapted to be screw-threaded into either end of said bore so as to protrude into said socket, the common axis of said socket and pivot being in the median plane of the fastening plate of one of said members.
- 35 4. The combination of a hinge-member having a socket, a second hinge-member having a bore open at each end, and a pivot 40 adapted to be secured in either end of said bore so as to protrude into said socket, the

common axis of said socket and pivot being in the median plane of the fastening plate of one of said members.

5. In a hinge, the combination of a hinge-member, which has a single knuckle located 45 midway of its hinge-plate and provided with a continuous bore therethrough having internal screw - threads, a second member having a single knuckle located at the upper end of its hinge-plate and provided with a 50 socket open at its bottom, of a unitary headless plug screw-threaded on its lower portion to engage said internal threads and cylindrical on its upper portion where it protrudes into said socket to constitute the 55 hinge-pivot, whereby said pivot can be longitudinally adjusted to any desired extent either upward or downward.

6. A door-hinge, comprising in combination a hinge-member having a knuckle with 60 a socket open at its bottom only, a complementary hinge-member having a knuckle with a continuous bore, a unitary plug with its lower portion engaging said bore and with its upper end protruding into said 65 socket to constitute an extended pivot-bearing therefor, and means operable from beneath for raising or lowering or for bodily inserting or entirely withdrawing said pivot from the lower end of said bore while the 70 door is in closed position within the doorway.

In testimony whereof I have signed this specification in the presence of two subscribing witnesses.

OSCAR C. RIXSON.
